WILLIAM G. SCHMIDLIN AND JEREMIAH W. DRISCOLL, OF NEW YORK, N. Y.

Letters Patent No. 77,408, dated April 28, 1868.

IMPROVEMENT IN REFLECTORS.

The Schedule referred to in these Letters Patent and making part of the same.

TO ALL WHOM IT MAY CONCERN:

Be it known that we, WILLIAM G. SCHMIDLIN and JEREMIAH W. DRISCOLL, of the city and State of New York, have invented and made a certain new and useful Improvement in Reflectors; and we do hereby declare the following to be a full, clear, and exact description of the said invention, reference being had to the annexed drawing, making part of this specification, wherein—

Figure 1 is a vertical section of the said reflector, and

Figure 2 is an inverted plan of the same.

Similar letters denote like parts.

Difficulty has heretofore been experienced in producing reflectors that would throw a nearly uniform light over a considerable extent of surface, such as a billiard-table, a store-counter, or show-window. The said reflectors increased the illumination of the object, but the distant parts were not near as light as those below the reflector.

Mirrors have been made with concave reflectors in their surfaces, but these are not adapted to use in conical reflectors over gas-lights.

The nature of our said invention consists in a polygonal conical reflector, in the sides of which concave dome metallic reflectors are introduced to throw the rays of light from a central burner or burners off the desired distance, and in as many different directions as there are concave reflectors, such rays of light crossing each other, and at the same time being sufficiently concentrated that the more distant parts of a billiard-table, a counter, a table, or a show-window, shall be illuminated almost the same as the parts beneath such reflector.

In the drawing, *a a* are the sections of metal, set together to form the polygonal conical reflector, and *b b* are the concave dome reflectors, introduced in these sections *a a*.

The sheet metal employed may be either smooth or corrugated. We prefer the latter, and the sections *a* may be in a general flat shape, as seen in fig. 1, but we prefer that the same should be curved, as seen by red lines in fig. 1.

The reflecting-surface itself is to be silvered or formed of other bright reflecting-material.

The sections *a* are provided with flanged edges, receiving the glass plates *c c* to protect the reflecting-surface from the action of the atmosphere. These glasses should be set in as nearly air-tight as convenient, in order that the reflector may be durable; and the glass employed may be corrugated, but we prefer that the same be plain sheet glass.

The pipe for the gas is provided at *d*, and *e* is the burner or burners. Over the burner, the reflector is formed with the central opening, as usual, and a smoke-cap may be suspended over the said opening, as seen at *e'*.

The dotted lines, fig. 1, illustrate the direction in which the rays of light are thrown, and it will be evident that the concave dome, introduced in the sections forming the polygonal reflectors, tend to throw the light off to a distance, and illuminate the article more uniformly.

This reflector may be employed with a lamp instead of a gas-burner.

What we claim, and desire to secure by Letters Patent, is—

The concave dome reflectors, introduced in the sections or sides of the conical polygonal reflector, as and for the purposes set forth.

In witness whereof, we have hereunto set our signatures, this thirteenth day of February, 1868.

WM. G. SCHMIDLIN,
J. W. DRISCOLL.
